Primary Examiner — T Chase Nelson*Assistant Examiner* — Rachel Wolfe(74) *Attorney, Agent, or Firm* — Novoclaims Patent Services LLC; Mei Lin Wong(57) **CLAIM**

The ornamental design for a projection lamp, as shown and described.

DESCRIPTION

FIG. 1 is a front perspective view of a projection lamp, showing my new design.

FIG. 2 is a bottom perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof; and,

FIG. 8 is a bottom view thereof.

The broken lines in the drawings depict portions of the projection lamp that form no part of the claimed design.

1 Claim, 8 Drawing Sheets(56)
